(57) **CLAIM**

The ornamental design for a portion of a display panel with a computer icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a portion of a display panel with a computer icon according to an example embodiment of the design;

FIG. 2 is a front view of a portion of a display panel with a computer icon in an example environment of use in conjunction with a graphical user interface according to another example embodiment of the design;

FIG. 3 is a front view of a portion of a display panel with a computer icon according to another example embodiment of the design; and,

FIG. 4 is a front view of a portion of a display panel with a computer icon in an example environment of use in conjunction with a graphical user interface according to another example embodiment of the design.

The broken lines in the figures, including the showing of a portion of a display panel of a computing device, with the various embodiments of the claimed design and the spaces therein are included for illustrating environmental structure only and form no part of the claimed design.
